UNITED STATES PATENT OFFICE.

PHILIP W. RAMER, OF RIVER FALLS, WISCONSIN.

SPRAYING MACHINE.

Application filed November 9, 1922. Serial No. 599,856.

This invention aims to provide a simple means whereby vegetation of various kinds may be sprayed with an insecticide, the action of a chemical in the making of the insecticide, serving to produce a gas which forces the insecticide out of a tank, it being unnecessary to use a pump for the purpose of securing pressure.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:

Figure 1 shows in longitudinal section, a device constructed in accordance with the invention, parts appearing in elevation, and the carrying straps being omitted; Figure 2 is a section wherein the device is shown inverted from the position of Figure 1; Figure 3 is a top plan of the structure shown in Figure 1; Figure 4 is a cross section on the line 4—4 of Figure 2; Figure 5 is a section on the line 5—5 of Figure 3; Figure 6 is a fragmental longitudinal section showing the attachment of the carrying straps. Figure 7 is a sectional view showing the mounting of the shaft on the lid.

In carrying out the invention, there is provided a tank 1 comprising a shell 2 and heads 3 and 4. The heads 3 and 4 are set inwardly from the ends of the shell 2, so that the tank 1 may be placed readily on a support of any desired kind, the tank being capable of end for end reversal. The head 3 carries a ring 6 provided with a flange 7. The head 3 is supplied on each side of the ring 6 with hook bearings 8.

A perforated receptacle 9 extends into the tank 1 through the head 3 and has a flange 10 resting on the flange 7 of the ring 6. A gasket 11 is mounted on the flange 10 of the receptacle 9. A lid 12 is superposed on the gasket 11 and has bearings 14 wherein a shaft 15 is mounted to rock, the shaft being provided with a handle 16 and being sup-

plied with a cam 17 adapted to bear on the lid 12. The ends of the shaft 15 are adapted to be engaged beneath the hook bearings 8 on the head 3.

The shell 2 of the tank 1 carries a valve 18 disposed relatively close to the head 3. A flexible hose 19 is assembled with the valve 18 and is connected to a rigid spout 20, which may be in the form of a pipe, a hand valve 21 being interposed in the spout 20. The spout 20 has an inclined end 27 carrying a nozzle 22 of any desired sort. The hose 19, the spout 20 and the nozzle 22 constitute an outlet conduit for the tank 1. A drain cock 23 is mounted on the shell 2 of the tank 1 and is located nearer to the head 3 than to the head 4, the drain cock 23 being spaced from the inner end of the perforated receptacle 9. Adjacent to the head 4, the shell 2 of the tank 1 carries a safety valve 24.

A saddle 25 extends longitudinally of the shell 2 of the tank 1. Carrying straps 26 are attached to one end of the saddle 25, and are provided at their opposite ends with hooks 28, adapted to be engaged with the saddle, as shown in Figure 6.

In practical operation, the receptacle 9 is removed from the tank 1, the tank being in the position of Figure 1. Water or other liquid is placed in the tank 1 to the level of the drain cock 23. The receptacle 9 is filled with some suitable material which, when wet, will produce a gas, and at the same time saturate the water or other liquid so as to produce an insecticide. The receptacle 9 is mounted in place on the ring 6, as shown in Figure 1, the gasket 11 being placed within the ring, and the lid 12 being mounted on the gasket, the ends of the shaft 15 being engaged beneath the hook bearings 8 on the head 3. Then, if the handle 16 be swung downwardly, into the position of Figure 1, the cam 17 on the shaft 15 will compress the lid 12 on the gasket 11 and effect an hermetic closure, the hook bearings 8 being of less height than the bearings 14 on the lid 12, and the shaft 15 having a slight movement in the bearings 14 in a direction parallel to the axis of the tank 1. Owing to the fact that the drain cock 23 is spaced from the inner end of the receptacle 9, longitudinally of the tank 1, it will be practically impossible to place enough liquid in the tank to enter the recep-

tacle 9 and saturate the contents thereof, when the tank stands in the position shown in Figure 1, provided that the valve or cock 23 is opened.

5 When it is desired to use the device, the tank 1 is inverted from the position of Figure 1 to the position of Figure 2, whereupon the liquid in the tank will saturate the contents of the receptacle 9 and the resulting 10 gas will be stored under pressure beneath the head 4, the safety valve 24 preventing the accumulation of a bursting pressure. When the parts are arranged as shown in Figure 2, the valve 18 may be opened and, 15 when it is desired to spray the plants or other vegetation, the valve 21 is opened, whereupon the liquid will be forced by the accumulated gas through the hose 19, the spout 20 and the valve 21, the inclination 20 of the end 27 of the spout being such that the nozzle may discharge readily upon the plants, trees, bushes or other vegetation. The valve 21 is so constructed that it may be manipulated readily, and, with this end 25 in view, a simple push-valve, of common form, may be supplied.

The device may be carried on the back of the operator, and, with this end in view, the saddle 25 is shaped to fit upon the back, 30 the carrying straps 26 being extended downwardly across the shoulders of the operator and the hooks 28 being engaged with the

lower edge of the saddle 25, after the showing of Figure 6.

What is claimed is:—

35 In a device of the class described, a tank comprising a head carrying a ring provided with a flange, hook-shaped bearings on the head in close relation to the ring, a lid within the ring, spaced bearings rigidly 40 mounted on the lid, a shaft having its ends mounted removably for rocking movement in the hook-shaped bearings of the head, the intermediate portion of the shaft being 45 permanently retained for rocking movement in the bearings of the lid, a cam on the shaft, a handle on the shaft and constituting means for rocking the shaft to cause the cam to bear directly on the lid and to move the lid toward the flange, the shaft having a 50 slight movement in the bearings of the lid, in a direction parallel to the axis of the tank, to permit the lid to move toward the flange, under the impulse of the cam, the handle being located between the bearings on the lid, thereby to prevent the shaft 55 from being detached from the bearings on the lid, by an endwise movement of the shaft.

55 In testimony that I claim the foregoing 60 as my own, I have hereto affixed my signature.

PHILIP W. RAMER.
